GLENN H. ALLEN AND THURLOE M. HAGENBOOK, OF EVANSVILLE, INDIANA, AS
SIGNORS TO THE INTERNATIONAL STEEL AND IRON COMPANY, OF EVANSVILLE,
INDIANA, A CORPORATION OF INDIANA

LIFT BRIDGE

Application filed September 6, 1927. Serial No. 217,768.

Our invention relates to lift bridges and more particularly to a system for accurately balancing lift bridge structures for enabling such structures to be readily operated with minimum motive power.

One of the objects of our invention is to provide a construction of lift bridge having means for accurately balancing the lift bridge after installation to meet a wide variety of operating conditions and to enable the bridge to be accurately balanced for movement to selected positions with the expenditure of minimum effort.

Another object of our invention is to provide a construction of counter-weight for a lift bridge structure wherein the center of gravity of the counter-weight and bridge structure may be shifted to a selected position for accurately balancing the lift bridge and permitting movement thereof in balanced condition to or from a substantially horizontal normal position to an angular position removed from the normal position.

Still another object of our invention is to provide a bascule bridge construction having a system of counter-weights each arranged for variation in the mass thereof for shifting and selectively fixing the center of gravity of the counter-weight and bridge structure for accurately balancing the bridge structure.

Another object of our invention is to provide a construction of counter weight for a bascule bridge, in which a plurality of counter-weights are provided each having pockets formed therein distributed through the counter-weight on opposite sides of a line passing through the normal center of gravity of the counter-weight and the bascule bridge structure, the pockets being arranged to receive removable sections of ballast for enabling the center of gravity of the bridge structure to be shifted to that degree necessary to accurately balance the bridge structure and permit movement of the bridge structure around a pivot with the expenditure of minimum effort.

Still another object of our invention resides in the arrangement of counter weights having removable sections therein and operating mechanism for shifting the position

of the bridge under control of the counter-weights, where the operating mechanism is capable of being longitudinally moved with minimum effort for shifting the entire bridge structure from a substantially horizontal position to an elevated position. 55

Our invention will be more clearly understood from the specification hereinafter following by reference to the accompanying drawings wherein:

Figure 1 is a side elevation of a bascule bridge structure embodying the counter-weight system and operating mechanism of our invention; Fig. 2 is a plan view showing the bridge structure and counter-weight system carried thereby in accordance with our invention; Fig. 3 is an end view partially in cross-section showing the operating mechanism of the bascule bridge structure and the arrangement of counter-weights on the bridge structure; Fig. 4 is an enlarged view showing the arrangement of the operating mechanism; Fig. 5 is a cross-sectional view taken on line 5—5 of Fig. 4 showing the manual actuator for elevating or lowering the bridge; Fig. 6 is a longitudinally cross-sectional view taken through one of the counter-weights employed in the bridge structure of our invention; Fig. 7 is a cross-sectional view taken on line 7—7 of Fig. 6; and Fig. 8 is a lateral cross-sectional view taken through the counter-weight on line 8—8 of Fig. 6. 60 65 70 75 80

In the construction of bascule bridges where rivers, streams, canals and other waterways are to be spanned and arrangements made to swing the bridge to a vertical position for clearance and passage of a vessel, the balancing of the bascule bridge is extremely important part of the design of the bridge structure. Bascule bridges are often employed at remote places where power is not available and the bridge must be capable of manual movement. The raising of a bascule bridge from a normally horizontal position to a substantially vertical position by manual power is extremely difficult unless the bridge has been accurately designed with respect to distribution of mass for the balancing of the bridge about its trunnions. Despite engineer- 85 90 95 100

ing care which may be taken in the design of lift bridges, experience in the field has shown that problems, not apparent to the engineer, in originally planning the bridge structure, 5 will arise and usually the balancing of the bridge becomes a cut and try method of pouring cement into a counter-weight and attempting by the mass of the counter-weight to counter-balance the bridge structure in just 10 that degree necessary for securing an accurate balance. Experience in the field has shown that the pouring of cement in the counter-weight is very likely to be misjudged, and often the counter-weight becomes of such mass 15 that the bridge cannot be balanced throughout its range of movement. The result is that it is necessary to chip away the cement from the counter-weight with the hope of obtaining just that mass necessary to effect balance of 20 the bridge. The removal of the poured cement from the counter-weight is a tedious and undesirable task and the results accomplished are often unreliable and the cut and try methods wasteful of time and energy.

25 In the bridge construction of our invention we provide a system of counter-weights on opposite sides of one end of the bridge, and through the counter-weights on opposite sides of a line which passes through the normal center of gravity of the counter-weight and bridge system, we distribute pockets so disposed in the counter-weights that ballast blocks may be received in positions both above and below the normal center of gravity of 30 the bridge and counter-weight structure. The arrangement of the removable ballast weights in the bridge construction enables the bridge structure to be accurately balanced to such a degree that the bridge may be moved to 35 either of the extreme positions under control of one man. The huge weight of the bridge structure may be so distributed by reason of the positioning of the ballast blocks in the pockets distributed throughout the counter- 40 weight system in the bridge structure of our invention that the inertia of the bridge to be shifted in position may be compensated, and the mechanical system described herein manually controlled for effecting movement of 45 the bridge structure.

In field experience it has been found that the normal unbalancing of a bascule bridge may be such that while the bridge may be raised manually after considerable effort, it 55 is not possible to lower the bridge under the same manual control. In such instances it has been necessary to resort to the expedient of attempting to pull the bridge down by cables drawn over the end of the bridge. Such 60 conditions as these are entirely overcome in the bridge structure and counter-weight system of our invention, where removable ballast may be added to or subtracted from the mass of the counter-weight on opposite sides 65 of a line normally passing through the cen-

ter of gravity of the counter-weight and bridge structure and through the structure of the bridge to effect an accurate balancing of the bridge in all of its positions.

Referring more particularly to the drawings we have illustrated in our invention as applied to a lift bridge of the bascule type having a cantilever truss structure 2 which is mounted to swing with respect to the foundation structure 1 on trunnions 3 mounted in bearing supports 4. The counter-weights for the bridge structure have been represented at 5 aligned with the extreme outer side beams 21 of the bridge structure 2. The counter-weights 5 comprise box-like frame structures bounded by segmental end portions 26, the side walls 27 and 28 of the counter-weights being bound together by tie rods 29 provided with suitable spacer members 30, the counter-weights having two walls thereof disposed substantially at right angles, while the top wall thereof forms an obtuse angle with respect to one of the end walls, the segmental wall 26 closing the counter-weight, thereby providing a box-like structure for receiving the cement ballast represented generally at 31. A cable 9 is attached to one end of the counter-weight at 10 and extends over the segmental shaped wall 26 to the take-up drum 7 which is carried by shaft 6. Cable 8 is attached at 11 to the opposite end of the counter-weight and is wrapped upon the take-up drum 7 in such manner that as the top cable 9 winds around the drum the bridge rises and the bottom cable 8 unwinds from the drum. The reverse is true when the bridge is lowered. Cement may be poured into the box-like structure of the counter-weight until it assumes a position represented by dotted line 12. The walls of the counter-weight may be built up and extended upon the frame structure to the full height of the segmental truss should it become desirable.

Throughout the counter-weight we provide pockets represented at 15-16-17-18-19 which may be opened from one side of the counter-weight by the removal of side plate members 15^a, 16^a, 17^a, 18^a and 19^a. Each of the pockets 15-16-17-18-19 extend from one side wall of the counter-weight to the opposite wall and provide braces for the walls of the counter-weight at the same time that space is provided to receive ballast blocks which we have represented generally at 32. The ballast blocks 32 are formed of such a size as will accommodate a multiplicity of rows of the ballast blocks. Upon the insertion of the required number of ballast blocks bracing means represented at 33 may be provided for securing the ballast blocks in position regardless of the angular movement of the bridge structure. The box-like pockets distributed throughout the counter-weight each have a row of retaining bolts represented at 34 projecting therefrom upon which the

- plate members may be secured for closing the pockets, the bolt members being anchored in the cement which fills in between the pockets during the normal filling of the counter-weight during the pouring operation. It will
- 5 be observed that the pockets are distributed on opposite sides of a line 14 which passes through the trunnions of the bridge and through the normal center of gravity of the bridge structure and counter-weight system.
- 10 This permits a shifting of the center of gravity of the bridge structure and counter-weight to a position above or below normal in accordance with the requirements of balancing the bridge structure.
- 15 The ability to manually elevate and lower the bridge structure depends largely upon the accuracy in the balancing of the bridge structure. The shaft 6 which carries the drums 7 is located in a pit 23 below the approach 24 of the bridge by means of a system of gears represented at 35 as enclosed within housing 20 from which projects the operating device 46. The main gear 36 is carried by shaft 6 and meshes with a smaller gear 37 which is keyed to another shaft 38. The shaft 38 carries the worm gear 39 in housing 40. A co-acting worm wheel 41 meshes with the worm gear 39 and may be moved by means of the operating device 46. Under conditions of accurate balancing a small force imparted to the operating device 46 may be multiplied to shift the position of the bridge to the desired position with a small expenditure of manual effort. The housing 20 may be suitably enclosed to protect the gearing with merely the operating device 46 projecting therefrom. By reason of the inherent self-locking construction of the worm wheels 39 and 41 the bridge when once moved to a selected position will remain in that position. An accurate balancing of the bridge over its entire range of movement may be secured by the shifting of the ballast blocks 32 to desired positions in the pocket within the area of the counter-weight thereby distributing the weight on either side of a line passing through the trunnions and the center of gravity of the counter-weight and bridge. In order to increase the rigidity of the bridge structure and counter-weight system, we provide a suitable truss structure 42 forming a tie between the counter-weights.
- 45 The bridge constructed herein has proven to be highly practical for fabrication and successful in its use, and while we have described a particular embodiment of our invention, we desire that it be understood that modifications may be made and that no limitations upon our invention are intended other than are imposed
- 50 by the scope of the appended claims.
- 55 What we claim as new and desire to secure by Letters Patent of the United States is as follows:
- 60 1. In a lift bridge a ballast portion, a bridge portion, trunnions between said portions, said
- ballast portion comprising a pair of counter-weights, each of said counter-weights comprising box-like enclosures for receiving a poured mass, said box-like enclosures having a substantially segmental shaped periphery, a plurality of pockets extending from one side wall of said counter-weights to the opposite side wall thereof, said pockets being disposed on opposite sides of a line passing through the center of gravity of said bridge, and being arranged to receive independent ballast blocks between the side walls of said counter-weight for selectively distributing the weight of the poured mass in predetermined manner throughout the counter-weights and cables extending over the segmental peripheries of said counter-weights for moving said weights in different positions about the trunnions of said bridge.
- 65 2. In a lift bridge structure, a ballast portion, a bridge portion, trunnions between said portions, said ballast portion comprising a pair of counter-weights on opposite sides of one end of the lift bridge structure, each of said counter-weights comprising box-like enclosures for receiving a mass of material, said box-like enclosures having a substantially segmental shaped periphery, said box-like enclosures being apertured throughout a plurality of portions of the area thereof and on opposite sides of a line passing through said trunnions and the center of gravity of said counter-weights and bridge, for forming pockets extending between one side wall of the box-like enclosures and the opposite side wall thereof for receiving individual ballast blocks between the side walls of said counter-weights for distributing the mass of the counter-weight in predetermined manner throughout the area thereof, and cables extending over the segmental peripheries of said counter-weights for moving said weights in different positions about the trunnions of said bridge.
- 70 3. In a lift bridge structure a ballast portion, a bridge portion, trunnions between said portions, said ballast portion including a counter-weight comprising a box-like enclosure for receiving a poured mass of material, said enclosure having a substantially segmental shaped periphery and a plurality of pockets distributed about said counter-weight in positions on opposite sides of a line passing through the normal center of gravity of the counter-weight and bridge structure, said pockets extending throughout the area between the side walls of said counter-weight being arranged to receive individual ballast blocks for distributing the mass of the counter-weight in predetermined manner and cables extending over the segmental peripheries of said counter-weights for moving said weights in different positions about the trunnions of said bridge.
- 75 4. In a lift bridge structure a ballast portion, a bridge portion, trunnions between said

portions, said ballast portion including a counter-weight, said counter-weight comprising a box-like frame arranged to receive a poured mass of material, said frame having a substantially segmental shaped periphery and a plurality of pockets formed in said box-like frame and extending between one side wall of said box-like frame and the other side wall thereof, and each closed by a removable plate extending over one side wall of the box-like frame, said pockets being arranged on opposite sides of a line passing through said trunnions and the center of gravity of said counter-weight and bridge and arranged to receive a plurality of individual ballast blocks for distributing the mass of the counter-weight in predetermined manner and a cable extending over the segmental shaped counter-weight for moving said weight in different positions about the trunnions of said bridge.

5. In a lift bridge structure a cantilever bridge pivotally mounted on trunnions adjacent one end thereof, a counter-weight in the plane of each truss of the bridge for balancing said cantilever bridge, each of said counter-weights comprising a substantially segmental shaped housing having a plurality of cells therein disposed on opposite sides of a line passing through the normal center of gravity of said counter-weight and cantilever bridge and through the trunnions, each of said cells being arranged to receive individual ballast blocks between the side walls 35 of the counter-weights for shifting the center of gravity of said counter-weight to that degree necessary to balance said bridge for movement about said trunnions and cables extending in surface contact with the segmental counter-weights for moving said weights in 40 different positions about the trunnions of said bridge.

In testimony whereof we affix our signatures.
